UNITED STATES PATENT OFFICE.

AUSTIN J. RUPPERT, OF FORRESTON, ILLINOIS.

CLOTHES-POUNDER.

1,152,438.

Specification of Letters Patent.

Patented Sept. 7, 1915.

Application filed September 28, 1914. Serial No. 863,922.

To all whom it may concern:

Be it known that I, AUSTIN J. RUPPERT, a citizen of the United States, residing at Forreston, in the county of Ogle and State 5 of Illinois, have invented certain new and useful Improvements in Clothes-Pounders, of which the following is a specification, reference being had to the accompanying drawings.

10 This invention relates to new and useful improvements in washing apparatus, and more particularly to what is known in this class as a clothes pounder, the main object of the present invention being the provision 15 of a device of this character which is so constructed as to thoroughly agitate the water when pounding the clothes and, at the same time provide for a thorough circulation of the water through the body of the pounder 20 when the same is pressed down upon the clothes in the water.

Another object of the present invention is the provision of a pounder including an inverted conical-shaped body having in its 25 lower or larger end an agitator which includes an annular ring and having extended across the ring a plurality of dividing walls whereby to thoroughly agitate the water upon the downward movement of the 30 pounder.

A further object of the present invention is the provision of a device of this character which will possess advantages in points of efficiency and durability, is inexpensive to 35 manufacture and, at the same time, is simple in construction and operation.

With the above and other objects in view, the invention consists in the novel features of construction, combination and arrangement of parts as will be hereinafter referred 40 to and more particularly pointed out in the specification and claim.

In the accompanying drawing forming a part of this application, Figure 1 is a side 45 elevation of a clothes pounder constructed in accordance with my invention, parts thereof being broken away and illustrated in cross section. Fig. 2 is a bottom plan view. Fig. 3 is a detail longitudinal sectional view. Fig. 4 is a plan view of a modified form of agitating member; and Fig. 5 is a horizontal sectional view illustrating a portion of still another modified form of agitator.

50 Referring more particularly to the draw-

ing, 1 indicates the body of a pounder, which is substantially an inverted truncated cone-shaped member having its lower edge bent upon itself to form a pocket for the reception of a stiffening wire, generally indicated 60 by the numeral 2 and which serves to strengthen the lower edge of the body and prevent the same from becoming bent or distorted. The body 1 is further provided at a point removed from the lower end with an 65 annular beading 3, extending inwardly into the body and forming a shoulder 4, upon which the inner edge of the agitator 5 is adapted to rest. This agitator may be secured in any suitable manner to the shoulder, but it is preferred to have the same 70 soldered. It will be understood that the agitator may be held in position by having the inner edge thereof riveted to the side walls of the body or otherwise secured in 75 position. It will be noted that by having the agitator arranged upon the shoulder, it will prevent the same from becoming pushed farther into the body.

The agitator itself includes an outer annular band 6, which as herein shown and described, is preferably corrugated, and in order to retain the band in its effective position, I provide a plurality of dividing walls 7 which extend radially from the center of the band and the outer ends thereof are soldered or otherwise secured to the inner wall of the same. The cross pieces or dividing walls 7 may be arranged within the band in several different ways, but as illustrated in 80 Fig. 2, these cross pieces or dividing walls include a single strip 8, which extends entirely across the space within the band and the ends thereof are secured to the band at diametrically opposite points. The remaining walls or dividing strips are formed by having a single piece bent upon themselves to form a substantially V-shaped member and having their intermediate portions soldered or otherwise secured to the central 85 portion of the strip 8, the ends thereof extending radially from the center of the band and are secured to the inner wall of the band by means of solder or other suitable fastenings. As stated above, these dividing 90 walls or strips 7 may be secured within the band in several different ways.

Arranged within the body 1, beyond the shoulder 4, is a circular plate 9, the central portion of which is integrally formed with 100

110

a socket member 10, the purpose of which will be hereinafter more fully set forth. The outer edge of the plate 9 is soldered or otherwise secured to the inner wall of the body 1 and is provided with a plurality of openings 11 which open into a chamber 12 and as illustrated in Fig. 3, the wall of the body 1 is provided with a plurality of openings 13 which form a direct communication between the chamber 12 and the exterior of the body, the openings 11 providing for communication between the chamber 12 and the interior of the body. Arranged over the outer face of the body and directly above the openings 13, are the hoods 14 which may be soldered or otherwise secured to the body, the lower ends of which are substantially larger than the inner ends thereof, whereby to provide for free exit of the water, which passes up through the body 1, through the chamber 12 and out through the openings 13.

It will be noted that by providing the hoods 14 upon the exterior of the body, it will prevent the water from splashing up on to the operator, but will be directed back into the tub or other receptacle.

The socket 10, which is arranged centrally within the upper end of the body 1, is adapted to receive the lower end of the handle member 15. This handle member may be secured in position in several different ways, but it is preferred to retain the same in position by soldering and in order to provide for rigid connection, I have arranged over the handle, a ferrule 16, the lower end of which projects down over the upper end of the socket 10 to a point adjacent the upper ends of the hoods 14. From this it will be apparent that a substantially strong connection is provided for connecting the handle to the body.

From the above description, it will be noted that I have provided a simple and durable clothes pounder, having an improved agitator therein which may be formed in several different ways, but it is preferable to have the same corrugated and including an outer corrugated band and a plurality of corrugated strips extending across the space within the band, whereby to thoroughly agitate the water as it passes into the body and also to provide for a thorough circulation of the water through the body and to this end, it will be noted that the openings 11 and 13 are provided so that the water may readily pass up through the body and out through the openings 13, the hoods 14 preventing further upward movement of the water, by directing the same back into the tub or other receptacle. The provision of the circular inclined plate 9 produces the annular chamber 12, communication being afforded between said chamber and the interior of the pounder 65 through the medium of the openings 11 in

the outer edge of said plate. The water entering through these openings strikes against the inclined body wall of the pounder and is directed upwardly through the openings 13 in the upper end of said body wall adjacent to the socket member 10. The water is ejected through these latter openings with considerable force and strikes against the inclined hoods 14 by which it is discharged downwardly and outwardly from the pounder body.

In Fig. 4, I have illustrated a slightly modified form of agitator which includes an outer ring 6' and a plurality of strips or dividing walls 7' radially extending from the center of the ring 6'. In this figure it will be noted that the outer ring 6' and the strips 7' are formed perfectly plain instead of corrugated as in the preferred form of the invention and it is to be understood that this form may readily replace the corrugated form, if so desired.

In Fig. 5, I have illustrated still another modified form of agitator, wherein the dividing walls or strips 7' are formed of single strips of material bent upon themselves to provide V-shaped members, the ends of which are secured to an outer band 6'', while the intermediate portions thereof are soldered or otherwise secured to the central ring 8' and it is to be understood that either one of the above noted modified forms can be used in place of the preferred form illustrated in Figs. 1 to 3 inclusive.

My device, as herein shown and described, is extremely simple in construction and can be manufactured and placed upon the market at a comparatively low cost.

It will be understood that while I prefer to fasten the cross pieces or walls 7 in the center of the ring, in a manner similar to that shown in Fig. 2, it will be understood that they may be fastened in any desired way, such as inserting between them a ring, as shown in Fig. 5 or they may be converged together and soldered, as shown in Fig. 4.

While I have shown and described the preferred form of my invention, it will be obvious that various changes in the details of construction and in the proportions may be resorted to for successfully carrying my invention into practice, without sacrificing any of the novel features or departing from the scope of the invention, as defined by the appended claim.

Having thus described my invention, what I claim is:—

A clothes pounder including a conical shaped body having a socket member secured to its smaller end and projecting within the body, a downwardly inclined circular plate fixed to said socket member and contacting at its outer edge with the body wall of the pounder, said plate constituting one wall of a water receiving chamber and pro-

vided in its outer edge with a series of recesses affording communication between said chamber and the interior of the pounder body, the body wall of the pounder being also provided adjacent to the socket member and inwardly of the recesses in said plate with a series of openings through which the water is ejected in the operation of the pounder, and directing hoods fixed to the

exterior of said body wall over the latter 10 openings.

In testimony whereof I hereunto affix my signature in the presence of two witnesses.

AUSTIN J. RUPPERT.
